US0D1065904S

(12) **United States Design Patent** (10) **Patent No.:** **US D1,065,904 S**
(45) **Date of Patent:** **** Mar. 11, 2025**

(54) **DRINKWARE LID**

(71) Applicant: **YETI Coolers, LLC**, Austin, TX (US)

(72) Inventor: **Dustin R. Bullock**, Austin, TX (US)

(73) Assignee: **YETI Coolers, LLC**, Austin, TX (US)

(**) Term: **15 Years**

(21) Appl. No.: **29/854,560**

(22) Filed: **Sep. 26, 2022**

(51) LOC (15) Cl. **07-01**

(52) **U.S. Cl.**

USPC **D7/300.1**

(58) **Field of Classification Search**

USPC D7/300, 300.1, 391, 392, 392.1, 591,
D7/597, 598, 900; D9/435, 446, 447,
D9/449

CPC A23L 2/00; B01F 13/00

(57) **CLAIM**

The ornamental design for a drinkware lid as shown and described.

DESCRIPTION

FIG. 1 is a top, front perspective view of a drinkware lid showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a top, front perspective view of a drinkware lid showing my new design in an alternate configuration;

FIG. 9 is a front view thereof;

FIG. 10 is a rear view thereof;

FIG. 11 is a right side view thereof;

FIG. 12 is a left side view thereof;

FIG. 13 is a top view thereof;

FIG. 14 is a bottom view thereof;

FIG. 15 is a top, front perspective view of a drinkware lid showing my new design in an alternate configuration;

FIG. 16 is a front view thereof;

FIG. 17 is a rear view thereof;

FIG. 18 is a right side view thereof;

FIG. 19 is a left side view thereof;

FIG. 20 is a top view thereof; and,

FIG. 21 is a bottom view thereof.

The broken lines depicting the remainder of the drinkware lid form no part of the claimed design.

1 Claim, 18 Drawing Sheets
